MOUNTING FOR BOBBIN RECEIVER FOR
WEFT REPLENISHING LOOMS

Gabriel C. Beatrice, Shrewsbury, and Kenneth J. Hall, Worcester, Mass., assignors to Crompton & Knowles Loom Works, Worcester, Mass., a corporation of Massachusetts

Application September 20, 1950, Serial No. 185,869

9 Claims. (Cl. 139—255)

1

This invention relates to improvements in receivers for spent bobbins in weft replenishing looms and it is the general object of the invention to provide a mounting for the receiver which can be swung forwardly to permit removal of the holder for the spent bobbins.

In weft replenishing looms it is common practice to provide a can or receptacle for the depleted bobbins which are expelled from the loom incident to weft replenishing operations. A form of receiver for such bobbins which has gone into use employs a cloth bag suspended from a metal frame which in the past has been supported by the loom. It is an important object of the present invention to provide a floor supported mounting for such a receiver including an upright pivoted to swing forwardly from its normal rear position to permit upward removal of the receiver.

It is a further object of the invention to provide a mounting for the receiver having a pivoted upright part on which is mounted a vertically adjustable carrier for the bobbin receiver so that the latter can be adjusted to the correct position for receiving the spent bobbins as they are discharged from the loom.

It is a still further object of the invention to provide a bobbin receiver mounting which is held in normal position by a yieldable member such as a spring which will permit forward swinging of the mounting and receiver when the latter is to be removed.

With these and other objects in view which will appear as the description proceeds, the invention resides in the combination and arrangement of parts hereinafter described and set forth.

In the accompanying drawings, wherein a convenient embodiment of the invention is set forth.

Fig. 1 is a front elevation of part of a weft replenishing loom having the invention applied thereto.

Fig. 2 is a side elevation looking in the direction of arrow 2, Fig. 1.

Fig. 3 is an enlarged horizontal section on line 3—3, Fig. 1, parts being removed.

Fig. 4 is a view similar to a part of Fig. 2 but showing the receiver in two positions, and

Fig. 5 is an enlarged vertical section on line 5—5, Fig. 3.

Referring particularly to Figs. 1 and 2 the loom frame 1 supports a lay 2 having a shuttle box 3 to receive a shuttle S. The shuttle box has a slot 4 in the under side thereof through which a depleted bobbin is discharged at the time of a weft replenishing operation. The depleted bob-

2

bin is guided downwardly and forwardly along a chute 5 which is secured to the lay below the shuttle box.

The bobbin receiver designated generally at R comprises a receptacle 6 shown in the form of a cloth bag having inner and outer vertical side walls 7 and 8, respectively, and front and back walls 9 and 10, respectively. The bag is open at the top and its side walls 7 and 8 are each provided with a hem 11. The lower part of the front wall 9 is provided with a pocket 12 which may be formed of cloth.

The cloth bag 6 is suspended from a metal supporting means or frame 15 having inner and outer rearwardly extending arms 16 and 17 which are inclined downwardly and rearwardly as shown in Fig. 2. The frame 15 has side members 20 and 21 extending generally in a vertical direction but preferably inclined downwardly and toward each other, see Fig. 1. The lower ends of the side members are joined by a horizontal bottom section or bar 22 which fits into the pocket 12. The frame 15 is preferably made of tubular material and each hem 11 has extending therethrough a wire 25 the rear end of which extends upwardly into the adjacent arm 16 or 17 and the front end of which extends through the corresponding side member 20 or 21 and is bent down as at 26. The wires 25 support the bag as shown in Fig. 2 and assist in holding the upper end of it open to present a bobbin receiving mouth 27. The upper ends of the side members 20 and 21 are preferably joined by a cross bar 28.

The matter thus far described may be similar to the form of receiver shown for instance in prior Patent No. 2,420,918.

The present invention relates more particularly to a support designated generally at A for the receiver R. The support A includes a foot or base 30 which may be secured to the floor under the lay by screws 31 passing through backwardly and forwardly extending slots 32 in the base. Extending upwardly from the base or foot are two spaced ears 35 and 36 which support a pivot pin 37 on which is mounted a shoe or the like 38.

Extending vertically from the shoe 38 is an upright or rod 40 held in vertically adjusted position on the shoe by a set screw 41 and having vertically adjustably mounted near the upper end thereof a carrier 42. The carrier includes a block 45 through which the rod 40 extends and to which it is secured in adjusted vertical position by a set screw 46. A flat sheet metal plate 50 extending transversely of rod 40 is secured as by screws

51 to the top of the block 45 and has the opposite ends thereof hooked to form pockets 52 to receive the side members 20 and 21.

As shown more particularly in Fig. 5 the shoe 38 cooperates with lock means L to hold the rod 40 normally in the bobbin receiving position shown in Fig. 2. The shoe has a rounded nose 55 to receive the curved end 56 of a leaf spring 57 secured as at 58 to the base 30. The curved end 56 normally fits around the nose 55 and exerts a yielding force thereon tending to hold the shoe 38 and upright rod 40 in normal position such as shown for instance in Fig. 2. The spring 57 will yield when the shoe 38 is turned around the pivotal connection 37 in a counterclockwise direction as viewed in Fig. 5. The shoe has a stop surface 59 which normally engages the base 30 to limit movement of the rod 40 rearwardly toward the lay, or to the right as viewed in Fig. 5.

When the receiver R and the mounting therefor are in the normal position shown in Fig. 2 and in full lines in Fig. 4 the rod 40 will be substantially vertical and the spring 57 by its engagement with the nose 55 will hold the receiver in its normal position with the mouth 27 located to receive bobbins which move downwardly along the chute 5. The side frame members 20 and 21 will be received by the pockets 52 and because of the fact that the members are inclined downwardly and toward each other the carrier 50 will support the receiver in a position determined by the vertical location of the block 45 along the rod 40.

When the bag 6 requires emptying because of an accumulation of depleted bobbins therein the operator will grasp cross bar 28 and swing the receiver and rod 40 forwardly from the full line to the abnormal dotted line position shown in Fig. 4, the spring 57 yielding upwardly slightly to permit this angular motion of the receiver. The bag 6 and frame 15 are then removed by upward motion, the side members 20 and 21 moving out of the pockets 52 incident to upward motion of the receiver and the cross bar sliding upwardly along rod 40.

The rod 40 will remain in the dotted line position shown in Fig. 4 due to its weight, but if desired the rounded part of the spring 56 may engage a surface 60 of the shoe 38 to exert a force to the left as viewed in Fig. 5 tending to hold the rod in its abnormal position. The under side of the shoe is provided with a stop surface 61 which will engage the top surface 62 of the base 30 when the mounting has been moved to its abnormal position.

After the bag has been inverted to empty its contents into a truck or the like provided for the purpose the operator will return the bag to its holding position with respect to the carrier 50, sliding the lower forward end of the bag and frame 15 along the rod 40 and guiding the members 20 and 21 into the pockets 52. By means of the cross bar 28 the frame and bag are then moved back to their normal position from the dotted line to the full line position shown in Fig. 4, the bent end 56 and spring 57 reestablishing yielding holding relation with respect to the shoe 38 to maintain the latter and the receiver in normal position.

If it be desired to raise the frame 15 and bag 6 to locate the mouth 27 nearer the bobbin chute 5 the set screw 46 can be loosened and block 45 slid upwardly along rod 40, after which the set screw can be tightened. A similar but more limited ad-

justment could be attained by slackening the set screw 41 and moving the lower end of the rod with respect to the shoe. While the carrier 50 has been shown in the form of a piece of flat sheet metal 5 the invention is not limited to this form of carrier.

From Fig. 2 it will be apparent that the receiver R is behind the rod 40 and tends due to its weight to turn in a clockwise direction around the carrier 42 and move the cross bar 22 forwardly, or to the left. The rod 40, however, limits this motion and cooperates with the cross bar to hold the mouth 27 of the bag in correct bobbin receiving position.

From the foregoing it will be seen that the invention sets forth simple means for supporting the bag 6 and frame 15 in such manner that it can be swung forwardly and then readily removed by an upward motion to permit emptying the contents of the bag. When the receiver is returned to its normal position its lower end can slide down around the rod 40 as the side members 20 and 21 are guided into the pockets 52. Vertical adjustment of the receiver can be effected by sliding the block 45 along the rod 40. The spring 57 normally overcomes any tendency of the receiver to move from the full line to the dotted line position indicated in Fig. 4, but the spring will yield to permit the receiver to be swung forwardly to its abnormal position from which it can be removed from its mounting. The under side of the shoe 38 has stop surfaces to engage the base 30 to limit angular motion of the rod 40 and receiver R around pivot pin 37. If desired the shoe 38 can be provided with a surface 60 to engage the spring 57 and enable the latter to assist gravity to hold the rod 40 in its abnormal position. Also, the rod 40 limits forward motion of cross bar 22 and holds the mouth 27 in correct bobbin receiving position when the parts are in normal position. The set screw 46 permits the block 45 and the carrier 42 to be adjusted angularly in a horizontal direction around the upright rod 40 to permit the receptacle to be aligned with the lay 45 without disturbing the base 30.

Having thus described the invention it will be seen that changes and modifications of the foregoing specific disclosure may be made without departing from the spirit and scope of the invention.

What is claimed as new is:

1. In a weft replenishing loom provided with a receptacle for spent bobbins discharged from the loom lay incident to replenishing operations, a frame supporting the receptacle having side members, and support means for the frame including a base in fixed position below the lay, an upright having the lower end thereof pivoted with respect to the base for movement to front and rear positions, means normally holding the upright in rear position, and a carrier on the upright engaging said side members and supporting the frame and receptacle, said upright being swingable to the forward position thereof and the side members being removable from the carrier by upward motion with respect to the upright.

2. In a weft replenishing loom provided with a receptacle for spent bobbins discharged from the loom lay incident to replenishing operations, a frame supporting the receptacle having side members, a base held in a stationary position below the lay, an upright extending upwardly from the base and pivotally mounted with respect thereto to swing to front and rear positions, lock means normally holding the upright in rear position, and

a carrier extending transversely of the upright having supporting engagement with the side members, said side members being movable upwardly with respect to and out of engagement with the carrier for removal of the frame and receptacle from the carrier after said upright has been swung to the forward position thereof.

3. In a weft replenishing loom provided with a receptacle for spent bobbins discharged from the loom lay incident to replenishing operations, a frame supporting the receptacle including side members which are inclined downwardly and toward each other, a stationary base below the loom lay, an upright member mounted on the base for swinging movement forwardly from the normal position thereof, and a carrier on the upright extending transversely of the latter and having pockets receiving the side members and normally supporting the frame and receptacle but enabling the side members by upward movement to be removed from the carrier when the upright has been swung forwardly.

4. In a weft replenishing loom provided with a receptacle for spent bobbins discharged from the loom lay incident to replenishing operations, a frame supporting the receptacle and having side members extending in a generally vertical direction and joined at their lower ends by a cross bar, a base in fixed position below the lay, an upright forward of the receptacle and frame pivotally mounted with respect to the base and extending upwardly from the latter and swingable forwardly from a normal rear position to an inclined abnormal position, and supporting means on the upright engaging the side members and causing forward movement of the latter and the receptacle when the upright swings to the abnormal position thereof, said supporting means enabling the side members by upward movement to be removed from the supporting means and the upright when in abnormal position being in position to limit forward movement of said cross bar and the frame during said upward movement of the side members.

5. In a weft replenishing loom provided with a receptacle for spent bobbins discharged from the loom lay incident to replenishing operations, a base mounted in fixed position beneath the lay, a shoe pivoted to the base to swing in a back and forth direction and having stop surfaces engageable with the base to limit angular motion thereof with respect to the base, a rod secured to the shoe and extending upwardly therefrom, carrier means on the rod adjacent to the upper end thereof supporting the receptacle for removal from said carrier means by upward motion, said carrier means causing the receptacle to swing around the axis of the shoe when the latter and the rod swing forwardly, and lock means normally engaging the shoe and holding the rod and receptacle in normal rear position, said lock means being movable to permit forward movement of the rod and receptacle from the normal position thereof.

6. In a weft replenishing loom provided with a receiver for spent bobbins discharged from the loom lay incident to replenishing operations, a base held in fixed position below the lay, a shoe pivoted on the base to swing backwardly and forwardly and having a stop surface normally engaging the base when the latter is in rear normal position, said shoe having a second stop surface engaging the base when the shoe swings

forwardly to an abnormal position, an upright secured to and moving angularly with the shoe, and supporting means for the receiver on the upright holding the receiver in position to receive spent bobbins when the first named surface of the shoe engages the base but causing the receiver to swing forwardly when the shoe moves to the abnormal position thereof, said receiver being removable from the supporting means by upward motion relative to the latter when the upright is in the abnormal position thereof.

7. In a weft replenishing loom provided with a receiver for spent bobbins discharged from the loom lay incident to replenishing operations, side members on the receiver joined at their lower ends by a cross bar, a base mounted in fixed position below the receptacle, an upright member mounted on the base for pivotal movement relative thereto to a forward position from the normal rear position thereof and located forward of said cross bar, and carrier means on the upright member supporting said side members and enabling the latter and the receiver to be removed by upward motion relative to the carrier for removal of the receiver to permit emptying of spent bobbins therefrom when the upright is in forward position, said upright when in forward position being located to guide said cross bar during said upward motion of the receiver.

8. In a weft replenishing loom provided with a receptacle for spent bobbins discharged from the loom lay incident to replenishing operations, a frame supporting the receptacle and provided with side members joined at the lower ends thereof by a cross bar, the side members and cross bar being forward of the receptacle, a carrier forward of said side members supporting the latter, and an upright member supporting the carrier, said frame and receptacle due to the weight thereof tending to move the cross bar forwardly, said upright being forward of and limiting forward movement of said cross bar.

9. In a weft replenishing loom provided with a receptacle for spent bobbins discharged from the loom lay incident to replenishing operations, a frame supporting the receptacle having side members, a base held in a stationary position below the lay, an upright extending upwardly from the base and pivotally mounted with respect thereto to swing to front and rear positions, a carrier extending transversely of the upright having supporting engagement with said side members, and means holding the carrier to the upright in angularly adjusted position around the upright, said side members being movable upwardly with respect to the carrier and out of engagement with the latter for removal of the frame and receptacle from the carrier after the upright has been swung to the forward position thereof.
